UNITED STATES PATENT OFFICE.

VALENTINE FOGERTY, OF BOSTON, MASSACHUSETTS.

IMPROVEMENT IN COLLAR-CLASPS.

Specification forming part of Letters Patent No. **43,190**, dated June 21, 1864.

To all whom it may concern:

Be it known that I, VALENTINE FOGERTY, a resident of Boston, in the county of Suffolk and State of Massachusetts, have invented a new and useful Collar-Clasp; and I do hereby declare the same to be fully described in the following specification and represented in the accompanying drawings, of which—

Figure 1 is a front view, and Fig. 2 an edge view, of the clasp as it appears when open. Fig. 3 is an edge view of it as closed.

My invention is for the purpose of attaching a collar to a shirt.

In the said drawings, A denotes a button, to whose shank, a, a plate, B, is fastened, and projects downward at a right angle to such shank. To the lower end of the plate B a plate or flap, C, is hinged, so as to be capable of being turned from the position represented in Fig. 2 to that represented in Fig. 3. A small eye or hole, b, is made through the plate C, and when the plate C is turned up into the position exhibited in Fig. 3 such eye closes on or receives a stud, D, (projecting from the plate B in extension of or line with the shank a,) which, in order to maintain the part C in

engagement with it sufficiently for the purposes required may be furcated or split, and formed as shown in the drawings.

In the use of the collar-clasp the button A is to be inserted in button-holes made in the neckband of the shirt, or the clasp is to be buttoned to the neckband by means of the button A. Next, the collar should be arranged in place around the neck of the shirt-band and have its ends buttoned on the stud D, after which the flap or part C should be turned up and on the stud D, so as to confine the laps of the collar in place thereon.

My invention is particularly useful for the attachment of a paper collar to a shirt while being worn, although it will answer equally well for connecting a linen or cloth collar or dickey thereto.

I claim as my invention—

The collar-clasp, made substantially as and for the purposes described.

VALENTINE FOGERTY.
